UNITED STATES PATENT OFFICE.

ORRIN G. FRANKS, OF CHAUTAUQUA, NEW YORK.

SPRING STRUCTURE.

Application filed March 30, 1923. Serial No. 628,902.

To all whom it may concern:

Be it known that I, ORRIN G. FRANKS, a citizen of the United States, residing at Chautauqua, in the county of Chautauqua 5 and State of New York, have invented a new and useful Improvement in Spring Structures, of which the following is a specification, reference being had to the accompanying drawing.

10 My improvement relates particularly to such spring structures as are used for bed bottoms and for seats.

The object of the invention is to produce such a structure in a form embodying a desirable degree of elasticity and durability and embodying a relatively small quantity of material whereby light weight and economic construction are attained.

In the accompanying drawings,

20 Fig. 1 is a plan of a spring structure embodying my improvement;

Fig. 2 is a side elevation of the same structure;

25 Fig. 3 is an end elevation of the same structure, parts being broken away;

Fig. 4 is an upright cross section on the line, 4—4, of Fig. 1, looking in the direction of the arrow;

30 Fig. 5 is a detail view of one of the springs;

Fig. 6 is an end view of another form of the structure;

35 Fig. 7 is an upright, longitudinal section on the line, 7—7, of Fig. 6, looking in the direction of the arrow;

Fig. 8 is an upright, transverse section on the line, 8—8, of Fig. 7, looking in the direction of the arrow;

40 Fig. 9 is an upright section on the line, 9—9, of Fig. 1;

Fig. 10 shows a spring in a form different from that shown by Fig. 5;

45 Fig. 11 is an end view similar to Fig. 3, excepting that the lower frame, C, is made narrower, in order to adapt the structure to be applied to a support narrower than the structure;

50 Fig. 12 shows a structure similar to Fig. 11, with transverse hangers applied to the side rails of a bed or similar structure and the spring structure being supported on said hangers;

55 Fig. 13 is an end view similar to Fig. 12, with the addition of transverse supporting bars combined with the structure;

Fig. 14 is a horizontal section on the line, 14—14, of Fig. 13;

Fig. 15 is an upright transverse section on the line 15—15, of Fig. 13;

Fig. 16 is a detail of a supporting bar. 60

In the form shown by the drawings, the structure includes three superposed, horizontal frames normally separated from each other by the springs. When downward pressure is applied to the upper frame, the 65 springs yield and allow the frames to approach each other.

Referring first to Figs. 1 to 6, inclusive, A is the upper frame. B is the middle frame, and C is the lower frame. The 70 structure is symmetrical, the upper and lower frames being alike, and the part of the structure at one side of the middle upright, longitudinal plane of the structure being like the part of the structure at the 75 opposite side of said plane. During use of the structure, the upper and lower frames maintain their dimensions; but during use the width of the lower frame varies with the downward and upward movement of the upper frame and the middle frame, the middle frame becoming wider during such downward movement and again becoming narrower during upward movement.

The upper frame consists of a border 85 wire, A¹, and three intermediate, longitudinal frame wires, A². The wire, A¹, is bent to form a rectangular parallelogram. The meeting ends of said wire extend into a sleeve, A³. The wires, A², have at each end 90 an eye, A⁴, surrounding the adjacent part of the wire, A¹. Tubular spacing members, A⁵, surround the wire, A¹, between the wires, A², and between said wires and the corners of the frame, A. Similar spacing 95 members are also placed on the side parts of the wire, A, and on the wires, A¹, the lengths of the spacing members on said side parts and the wires, A¹, being adapted to the spacing of the springs from each other, 100 as will be described further on.

The lower frame, C, is a duplicate of the frame, A, and is composed of wires and eyes and spacing members, C¹, C², C³, C⁴ and C⁵, corresponding, respectively, to the parts, 105 A¹, A², A³, A⁴ and A⁵, of the upper frame.

The middle frame, B, is a duplicate of the frames A and C, excepting that at each end of the structure the border wire, B¹, is parted at the middle of said end, the ends 110

abutting against each other, and a loose sleeve, B^2 , surrounding said ends so as to permit horizontal sliding of the ends in the sleeves, whereby the two halves of the frame, B , may move away from and toward each other, the movement toward each other ceasing when the ends of the wire, B^1 , abut.

On the frame, B , are two intermediate frame wires, B^3 , which are parallel to and between the outer intermediate wires, A^2 and C^2 . At their ends, the wires, B^3 , have eyes, B^4 , surrounding the border wire, B^1 . There is no intermediate wire, B^3 , between the intermediate wires, A^2 and C^2 , in the middle, upright, longitudinal plane of the structure.

M-shape springs, E , connect the frames, A , B and C , and support the frames, A and B , above and on the frame, C . These springs are arranged in planes which are upright and transverse to the length of the structure. At the middle of each spring is an eye or loop, E^1 , surrounding one of the wires or bars, B^1 , of the frame, B . At the upper angle, the spring has an eye or loop, E^2 , surrounding one of the intermediate wires, A^2 , and at the lower angle the spring has a loop or eye, E^3 , surrounding the corresponding wire or bar, C^2 . At the outer end of the upper arm, E^5 , the spring has an eye or loop, E^4 , which surrounds one of the wires or bars, A^1 , of the upper frame, A . An eye or loop, E^6 , on the outer end of the lower arm, E^7 , surrounds the corresponding wire or bar, C^1 , of the lower frame.

Along the upright, longitudinal plane in which lie the intermediate wires, A^2 and C^2 , between which there is no intermediate wire, B^3 , on the middle frame, the springs are directed oppositely, the springs at one side of said plane having the eyes, E^2 and E^3 , in said plane and having the eyes, E^4 , E^1 and E^6 , engaging the intermediate wires which are next to said plane and in a plane which is parallel to the first mentioned plane.

The intermediate wires or bars, A^2 and C^2 , between which there is no intermediate wire or bar, B^3 , are, for convenience, designated the primary intermediate bars, and the upright, longitudinal plane in which the primary bars lie is called the primary plane. For further convenience, the other intermediate bars or wires of the three frames are called secondary bars, while the upright planes in which those secondary bars lie are called secondary planes.

The springs at opposite sides of and reaching into the primary plane are oppositely directed at opposite sides of said plane, the eyes, E^2 , engaging the primary bar, A^2 , of the upper frame, and the eyes, E^3 , engaging the primary bar, C^2 , of the lower frame, while the eyes, E^4 , E^1 and E^6 , engage, respectively, the bars, A^2 , B^3 and C^2 , in the

next secondary plane. Thus the arms, E^5 and E^7 , of these springs form the borders of a diamond-shape figure. Going toward the borders from the secondary planes reached by the springs which are applied to the primary plane as above described, the springs are positioned to correspond with the springs already described. That is to say, the springs are so placed as to direct the eyes, E^2 and E^3 , toward the primary plane and to engage, respectively, the bars engaged by the eyes, E^4 and E^6 , in the above-mentioned primary planes, while the eyes, E^4 , E^1 and E^6 , engage the wires in the next upright plane. In the form shown in the drawings, this plane is the plane of the border wires of the upper, middle, and lower frames. If the structure were wider, this engagement would be with the secondary bars of another secondary plane.

When the springs above described have been put into position, they will be in a plane which is upright and transverse to the length of the structure. Other sets of said springs are similarly placed in transverse, upright planes crossing the structure at different places. Such planes are preferably spaced from each other equal distances, such distances being adapted to bring into the structure the number of springs suited to give the finished structure the desired sustaining power coupled with the desired elasticity or resiliency between said planes, tubular spacing members, A^5 , surround the border wire, A^1 , and the intermediate wires, A^2 , and similar spacing members, B^5 , surround the border wire and the intermediate wires of the middle frame and similar spacing members, C^5 , surround the border wire and the intermediate wires of the lower frame. The purpose of said spacing members is to give to the springs their positions on the wires with reference to the length of the structure.

When downward pressure is applied to the upper surface of the structure sufficient to compress the springs, all the eyes or loops, E^1 , of the springs are forced sidewise away from the upright longitudinal primary plane. This involves sidewise movement of the two halves of the middle frame, the meeting ends of the border wire, C^1 , of the middle frame sliding in the sleeves, C^3 , which loosely surround said ends. When such downward pressure is removed, the springs resume normal position, whereby the frames, A and B , are moved into their normal positions. This involves movement of the two halves of the frame, B , toward the upright primary plane.

The bed mattress or seat cushion is to be supported by the spacing tubes and the upper arms, E^5 , of the springs. If more such support is desired, the longitudinal tubes of the upper frame may be divided

and horizontally supporting links, A⁶, having eyes or loops, A⁷, being placed between the spacing sections thus formed and extending from one longitudinal wire frame 5 to the other, the eyes or loops, A⁷, engaging said wires. Thus these supporting links are in lines which are parallel to the transverse upright planes of the springs. Such supporting links are shown on the left hand 10 part of Figs. 1 and 2, and in Fig. 9.

The tubular spacing members, A⁵, B⁵ and C⁵, are preferably made of coiled wire, as shown by the drawings, in order that desired thickness and a surface finish may be attained; for in the making of these tubes of 15 wire, a wire may be used which has a bright and smooth surface which does not require enameling or other treatment to produce a desired surface.

20 It is to be understood that the springs, D, are to be of suitable thickness and strength and flexibility and are to be so spaced from each other as to give the completed structure the desired strength and elasticity. The 25 height of the springs is also to be varied to meet practical requirements. It is also to be understood that the frames, A, B and C, are to be of any desired length and width and that any desired number of intermediate wires, A², B² and C², may be used.

In the form illustrated by Figs. 6, 7 and 8, horizontal coiled springs, B⁷, connect the intermediate frame wires, B³, at opposite sides of the upright, longitudinal primary 35 plane, said coiled springs having eyes, B⁸, surrounding said intermediate wires; and such coiled springs are also substituted for the sleeves, B², of the form shown by Figs. 1, 2 and 3. The spring, B⁷, surrounds the 40 border wire, B¹, and has its ends joined to the intermediate wires by means of the eyes, B⁸. These springs, B⁷, resist the lateral movement of the two sections of the middle frame, this resistance supplementing the resistance offered by the springs, E.

45 In Fig. 5, the loops or eyes, E¹, E² and E³, are formed by folding the wire. In Fig. 10, the spring is of the same shape as in Fig. 5, excepting that the wire is crossed to form the eyes, E¹, E² and E³.

At times it will be desirable to apply this spring structure to a support which is narrower than the upper surface of the structure. To adapt the structure to be so applied, the lower frame, C, may be made narrower than the frames, A and B, as is shown in Fig. 11, the sides of the frame, C, resting on cross slats, S, which rest on bed rails, R, as shown in Fig. 11 or on hangers, H, as shown in Fig. 12. In this form, the arms, E⁷, of the outer springs, E, are made shorter than the upper arms, E⁵, of said springs.

In the form shown by Figs. 13, 14, 15 and 65 16, the lower frame, C, is made narrow as in Fig. 11, and hanger bars, F, are applied

at the ends of the frames, B and C, the intermediate wires, C², extending through apertures, F¹, and the border wire, B¹, extending through eyes, F², formed on upward extensions of said bars. Said eyes are made 70 large enough to allow the border wire, C¹, to move downward and outward during the downward movement of the middle frame. These hanger bars, F, may be flat metal bars placed in an upright plane with the ends 75 turned to form the eyes, F². Such bars may also be similarly placed intermediate the ends of the structure. The eyes, F², and the side border wire are to rest on the side rails, R, of a bed or similar structure. 80

From the foregoing description it will be seen that the middle frame, B, may be termed a divided frame or sectional frame, and that the primary plane along which that frame is divided may also be termed the division plane. It is also to be observed that the arms, E⁸ and E⁹, of the springs fold and unfold somewhat after the manner of the folding and unfolding of the link members of a toggle, and that therefore this part of the structure may be said to be of a toggle-form. 90

I claim as my invention,

1. In a spring structure, the combination with an upper frame and a lower frame, of 95 upright springs having their upper ends joined to the upper frame and having their lower ends joined to the lower frame and said springs being formed to cause sidewise movement between their ends during 100 compression, the springs at each side of the upright primary plane of the structure being set to cause the said sidewise movement to be away from said plane, and means located between the upper and lower frames at each side of said plane and joined to the springs, whereby the springs at each side of said plane are held for movement in unison, substantially as described.

2. In a spring structure, the combination of upright springs all having a middle V-form part transverse to two of the borders of the structure, an upper frame joined to the upper ends of the springs, a lower frame joined to the lower ends of the 105 springs, and middle frame sections joined to the angles of the V-form parts of the springs, the springs to which one section is joined being directed away from the other section, substantially as described. 110

3. In a spring structure, the combination of upright springs all having a middle foldable part extending parallel to two of the borders of the structure, such foldable parts moving horizontally during downward compression of the springs, an upper frame joined to the upper ends of the springs, a lower frame joined to the lower ends of the springs, and two middle frame sections joined to the middle foldable parts of the 125 130

- springs, the springs to which one of the sections is joined being turned in opposition to the springs to which the other section is joined, substantially as described.
5. 4. In a spring structure, the combination of an upper frame and a lower frame, and two middle frame sections, and upright springs joined to the upper and the lower frames and the middle frame sections and adapted to move said sections from each other during compression of the springs, substantially as described.
10. 5. In a spring structure, the combination with an upper frame and a lower frame and a middle divided frame, of upright springs in planes transverse to the division plane of the middle frame and said springs having horizontal upper arms secured to the upper frame and said springs having horizontal lower arms secured to the lower frame and said springs having between said arms a folded part joined to one of the middle frame sections, the springs at one side of the division plane being directed in opposition to the springs at the other side of said plane, substantially as described.
15. 6. In a spring structure, the combination with an upper frame and a lower frame and a middle divided frame, of upright springs in planes transverse to the upright plane on which the middle plane is divided and the springs having horizontal upper arms secured to the upper frame and having lower arms secured to the lower frame and said springs having between the arms a folded part joined to the middle frame sections, the springs joined to one section of the middle frame being directed in opposition to the springs joined to the other section of the middle frame, substantially as described.
20. 7. In a structure of the kind described, the combination of three superposed frames, the middle frame being divided along a primary plane, springs joined to said frames in a manner permitting downward compression of the springs, the parts of said springs joined to the middle frame moving sidewise during downward movement, the sidewise movement at each side of said plane being away from said plane, whereby the middle plane sections move sidewise away from each other during downward movement, substantially as described.
25. 8. In a structure of the kind described, the combination of three superposed frames, the middle of which is divided along an upright primary plane, and M-shape springs having one arm secured to the upper frame and having the other arm secured to the lower frame and having its middle part joined to the middle frame, the middle parts of the springs at each side of said plane being directed away from said plane, substantially as described.
9. In a spring structure, the combination with upper and lower frames, each comprising a border wire and intermediate wires, of upright springs having their upper ends joined to the upper frame and having their lower ends joined to the lower frame and said springs being formed to cause lateral movement between their ends during compression, the springs at each side of the upright primary plane of the structure being set to cause the said sidewise movement to be away from said plane, and means located between the upper and lower frames at each side of said plane and joined to the springs, whereby the springs at each side of said plane are held for movement in unison, substantially as described.
30. 10. In a spring structure, the combination with an upper frame and a lower frame, each comprising a border wire and intermediate wires, and two middle frame sections, of upright springs joined to the upper and the lower frames and the middle frame sections and adapted to move said sections from each other during compression of the springs, substantially as described.
35. 11. In a spring structure, the combination with upper and lower frames, each comprising a border wire and intermediate wires, and a middle divided frame, of upright springs in planes transverse to the division plane of the middle frame and said springs having horizontal upper arms secured to the upper frame and said springs having horizontal lower arms secured to the lower frame and said springs having between said arms a folded part joined to one of the middle frame sections, the springs at one side of the division plane being directed in opposition to the springs at the other side of said plane, substantially as described.
40. 12. In a spring structure, the combination of upright springs all having a middle V-form part transverse to two of the borders of the structure, the upper frame joined to the upper ends of the springs, a lower frame joined to the lower ends of the springs, a middle frame including a border wire divided at opposite borders of the frame and sleeves loosely surrounding the meeting ends of said wires and said frame sections being joined to the angles of the V-form parts of the springs, the springs to which one section is joined being directed away from the other section, substantially as described.
45. 13. In a spring structure, the combination of an upper frame and a lower frame, and a middle frame including a border wire divided at opposite borders of the frame and sleeves loosely surrounding the meeting ends of said wires and upright springs joined to the upper and the lower frames and the middle frame sections and adapted to move said sections from each other during compression.

pression of the springs, substantially as described.

14. In a spring structure, the combination of upright springs all having a middle V-form part transverse to two of the borders of the structure, an upper frame joined to the upper ends of the springs, a lower frame joined to the lower ends of the springs, middle frame sections joined to the angles of the V-form parts of the springs, the springs to which one section is joined being directed away from the other section, and horizontal springs joining said sections and yieldingly drawing said sections toward each other, substantially as described.

15. In a spring structure, the combination of upright springs all having a middle foldable part extending parallel to two of the borders of the structure, such foldable parts moving horizontally during downward compression of the springs, an upper frame joined to the upper ends of the springs, a lower frame joined to the lower ends of the springs, two middle frame sections joined to the middle foldable parts of the springs, the springs to which one of the sections is joined being turned in opposition to the springs to which the other section is joined, and horizontal springs joining said sections and yieldingly drawing said sections toward each other, substantially as described.

16. In a spring structure, the combination of an upper frame and a lower frame, two middle frame sections, and upright springs joined to the upper and the lower frames and the middle frame sections and adapted to move said sections from each other during compression of the springs, and horizontal springs joining said sections and yieldingly drawing said sections toward each other, substantially as described.

17. In a spring structure, the combination with an upper frame and a lower frame and a middle divided frame, of upright springs in planes transverse to the division plane of the middle frame and said springs having horizontal upper arms secured to the upper frame and said springs having horizontal lower arms secured to the lower frame and said springs having between said arms a folded part joined to one of the middle frame sections, the springs at one side of the di-

vision plane being directed in opposition to the springs at the other side of said plane, and horizontal springs joining said sections and yieldingly drawing said sections toward each other, substantially as described.

18. In a spring structure, the combination with an upper frame and a lower frame and a middle divided frame, of upright springs in planes transverse to the upright plane on which the middle plane is divided and the springs having horizontal upper arms secured to the upper frame and having lower arms secured to the lower frame and said springs having between the arms a folded part joined to the middle frame sections, the springs joined to one section of the middle frame being directed in opposition to the springs joined to the other section of the middle frame, and horizontal springs joining said sections and yieldingly drawing said sections toward each other, substantially as described.

19. In a spring structure, the combination with three superposed frames, the middle frame being divided along an upright primary plane, of springs arranged in toggle form relative to said plane, the upper parts of the toggles being joined to the upper frame and the lower parts of the toggles being joined to the lower frame and the middle parts of the toggles being joined to the middle frame sections, the toggles joined to one of said sections being directed in opposition to the toggles joined to the other section, and horizontal springs joining said sections and yieldingly drawing said sections toward each other, substantially as described.

20. In a spring structure, the combination of an upper frame and a lower frame and two middle frame sections, means yieldingly joining the upper frame and the middle sections and the lower frame and tending to separate said sections horizontally during downward pressure on the upper frame, and horizontal springs joining said sections and yieldingly drawing said sections toward each other, substantially as described.

In testimony whereof I have signed my name, this 26th day of March, in the year one thousand nine hundred and twenty-three.

ORRIN G. FRANKS.
